Des. 221,276
Patented July 27, 1971

221,276

CRATE FOR MATERIAL HANDLING

Houston Rehrig, 3730 E. 26th St.,
Los Angeles, Calif. 90023

Filed Feb. 19, 1970, Ser. No. 21,503

Term of patent 14 years

Int. Cl. D9—05

U.S. Cl. D9—177

FIG. 1

FIG. 2

FIG. 3

FIG. 1 is a front perspective view of a crate for material handling showing my new design;

FIG. 2 is a side elevation view thereof, the opposed side being identical thereto; and

FIG. 3 is a top plan view thereof on a reduced scale.

The bottom of the design is substantially plain and unornamented.

I claim:

The ornamental design for a crate for material handling, substantially as shown and described.
